A. ANGEL

JOINT AND METHOD OF MAKING SAME

Original Filed Nov. 28, 1921

UNITED STATES PATENT OFFICE.

AUGUSTUS ANGEL, OF BROOKLYN, NEW YORK, ASSIGNOR TO SIGNODE SYSTEM, INC., OF CHICAGO, ILLINOIS, A CORPORATION OF DELAWARE.

JOINT AND METHOD OF MAKING SAME.

Application filed November 28, 1921, Serial No. 518,251. Renewed August 12, 1927.

This invention relates to tension resisting joints in flat metallic box strapping, and particularly to a reinforced joint made by forming interlocking conjoint deformations 6 simultaneously in two overlapped box strap ends and a reinforcing member.

It is an object of the invention to provide a joint of the character described, simple and efficient in construction and economical 10 to make. Among the advantages of the present invention is the fact that no special sleeve element is necessary.

In the drawings which represent an illustrative embodiment of the invention:

15 Fig. 1 is a perspective view of a box with the joint of my invention applied,

Fig. 2 is a perspective view of the component parts of the joint, comprising box strap ends,

20 Fig. 3 is a side elevation of the joint,
Figs. 4 and 5 are a top and bottom plan view respectively, and

Fig. 6 is a cross sectional view of the joint on line 6—6 of Figure 4.

25 In the drawings are shown a pair of overlapped box strap ends 1 and 2, in the position they would assume if they were the ends of a binder applied under tension about a box or package. The joint 3 (of which two are shown) is provided for the purpose 30 of securing these ends together. It will be recognized as of the same type as the joint of the Flora Patent No. 1,252,680, January 8, 1918, formed by deforming the straps 35 edgewise or out of their normal cross sectional shapes to produce tension resisting conjoint interlocking deformations therein. Such a joint for most efficient action requires reinforcement, heretofore in the form of a 40 special reinforcing girth or sleeve. This reinforcement I provide, not by the use of a separate sleeve as heretofore employed, but by doubling back the top strap end upon itself, as shown at 4, and by thereafter forming the conjoint interlocking deformations 45 in three strap thicknesses simultaneously.

The result of this method is the production of a reinforced joint capable of withstanding heavy tension in which the reinforcement does not require the manufacture 50 or manipulation of a special sleeve element. Furthermore the reinforcement is automatically graduated in accordance with the duty

imposed upon the joint. Thus to withstand the strains imposed upon binders used for 55 heavy boxes, bales, etc., heavy strap is used; while for lighter boxes it is customary to use lighter strap. In the joint of this invention the reinforcement will automatically correspond to the thickness of the strap. 60

Since the operation of crimping the strap is performed with hand tools, it is of advantage that the reinforcement be graduated to the thickness of the strap. This method obtains therefore the advantage of a heavy reinforcing element where heavy reinforcement is necessary and a lighter reinforcement where light reinforcement is sufficient, without making it necessary to manufacture 65 separate reinforcing girths and at the same 70 time eliminates the expense or time involved in the assembly of strap ends in such girths, or the manipulation of the girths.

Having described my invention, I claim:

1. The method of forming a reinforced 75 joint in a flat tensional binder which consists in overlapping the ends of the binder, bending back one end on the overlap to provide three thicknesses of material and then performing conjoint joint forming operations on said three thicknesses.

2. The method of forming a reinforced joint in a tensional binder which consists in overlapping the ends of the binders, bending back one end on the overlap to provide 80 three thicknesses of material and then forming, simultaneously, interlocked deformations in said three thicknesses.

3. The method of forming a reinforced joint in a tensional binder which consists in 85 overlapping the ends of the binders, bending back one end on the overlap to provide three thicknesses of material and then forming marginal deformations simultaneously in the three thicknesses of metal.

4. The method of forming a reinforced joint in a tensional binder which consists in overlapping the ends of the binders, bending back one end on the overlap to provide 90 three thicknesses of material and then distorting the cross sectional shape of the three thicknesses of metal by forming conjoint interlocked edgewise crimps therein.

5. The method of forming a tension 95 resisting joint in box binders or the like, which consists in compounding two overlapped

- ends of said binders, with a short length of binder material integral with one of the ends, into a tension resisting joint, all portions of which extend longitudinally of the binder.
6. The method of forming a reinforced joint in tensional binders which consists in overlapping the ends of the binders, bending back one end on the overlap to provide three thicknesses of material, and then deforming said three thicknesses in a manner to lock said thicknesses together against separation in a direction at right angles to the face of the binders, and thereby sealing the joint.
7. The method of making a tension resisting joint in flat tensional box strapping which consists in overlapping two ends of said box strapping, applying another layer 20 of the same material integral with one of the ends, and performing lateral crimping operations on the triple thicknesses of material thus provided.
8. A joint formed by the simultaneous deformation of two overlapped flat metallic tensional binder ends, and a portion of one of said binder ends doubled back upon the two thicknesses involved in the overlap, the interlock between said binder ends being effected solely between edges extending substantially longitudinally of the binder.
9. A joint formed by the simultaneous deformation of three thicknesses of a flat metallic tensional binder comprising two binder ends superposed, and a third strip of substantially the same width integral with one end added thereto for reinforcing purposes, all portions of said two binder ends and said third strip extending longitudinally of said binder.
10. A joint for box strapping or the like, comprising in combination a pair of superposed and overlapped box strap ends, a third strip of material integral with one end of substantially the same thickness applied thereon, and conjoint interlocking deforma-
- tions formed simultaneously in said three thicknesses.
11. The method of forming a reinforced joint in a flat tensional binder which consists in overlapping two ends of the binder, bending back one end on the overlap to provide three thicknesses of material, and then performing conjoint joint forming operations on the said three thicknesses, the bent back end being folded about the other two thicknesses.
12. The method of forming a tension resisting joint in box binders which consists in overlapping two ends of the binder, applying another layer integral with one end of said binder, and performing joint forming operations on the three thicknesses of material, the last mentioned layer being crimped about the other two layers.
13. A joint for box strapping comprising a pair of superposed and overlapped box strap ends, a third strip of material integral with one of the ends applied thereto, and conjoint interlocking deformations formed in the three thicknesses, the third strip being crimped about the other two thicknesses.
14. A joint for box strapping comprising a pair of superposed and overlapping box strap ends, a third strip of material integral with one of the ends applied thereto and a plurality of conjoint interlocking deformations formed in the three thicknesses.
15. A joint for box strapping comprising a pair of superposed and overlapping box strap ends, a third strip of material integral with one of the ends applied thereto and a plurality of conjoint interlocking deformations formed in the three thicknesses, said deformations being longitudinally spaced apart from one another.

In witness whereof, I hereunto subscribe my name this 12th day of November, A. D., 1921.

AUGUSTUS ANGEL.

ends of said binders, with a short length of binder material integral with one of the ends, into a tension resisting joint, all portions of which extend longitudinally of the binder.

6. The method of forming a reinforced joint in tensional binders which consists in overlapping the ends of the binders, bending back one end on the overlap to provide 10 three thicknesses of material, and then de-forming said three thicknesses in a manner to lock said thicknesses together against separation in a direction at right angles to the face of the binders, and thereby sealing 15 the joint.

7. The method of making a tension resisting joint in flat tensional box strapping which consists in overlapping two ends of 20 said box strapping, applying another layer of the same material integral with one of the ends, and performing lateral crimping operations on the triple thicknesses of material thus provided.

8. A joint formed by the simultaneous 25 deformation of two overlapped flat metallic tensional binder ends, and a portion of one of said binder ends doubled back upon the two thicknesses involved in the overlap, the interlock between said binder ends being effected solely between edges extending substantially longitudinally of the binder.

9. A joint formed by the simultaneous deformation of three thicknesses of a flat metallic tensional binder comprising two binder 35 ends superposed, and a third strip of substantially the same width integral with one end added thereto for reinforcing purposes, all portions of said two binder ends and said third strip extending longitudinally of said binder.

10. A joint for box strapping or the like, comprising in combination a pair of superposed and overlapped box strap ends, a third strip of material integral with one end of 45 substantially the same thickness applied thereon, and conjoint interlocking deforma-

tions formed simultaneously in said three thicknesses.

11. The method of forming a reinforced joint in a flat tensional binder which consists in overlapping two ends of the binder, bending back one end on the overlap to provide 50 three thicknesses of material, and then performing conjoint joint forming operations on the said three thicknesses, the bent 55 back end being folded about the other two thicknesses.

12. The method of forming a tension resisting joint in box binders which consists in overlapping two ends of the binder, applying another layer integral with one end 60 of said binder, and performing joint forming operations on the three thicknesses of material, the last mentioned layer being crimped about the other two layers. 65

13. A joint for box strapping comprising a pair of superposed and overlapped box strap ends, a third strip of material integral with one of the ends applied thereto, and conjoint interlocking deformations 70 formed in the three thicknesses, the third strip being crimped about the other two thicknesses.

14. A joint for box strapping comprising a pair of superposed and overlapping box 75 strap ends, a third strip of material integral with one of the ends applied thereto and a plurality of conjoint interlocking deformations formed in the three thicknesses. 80

15. A joint for box strapping comprising a pair of superposed and overlapping box strap ends, a third strip of material integral with one of the ends applied thereto and a plurality of conjoint interlocking deformations formed in the three thicknesses, 85 said deformations being longitudinally spaced apart from one another.

In witness whereof, I hereunto subscribe my name this 12th day of November, A. D., 90 1921.

AUGUSTUS ANGEL.

CERTIFICATE OF CORRECTION.

Patent No. 1,662,914.

Granted March 20, 1928, to

AUGUSTUS ANGEL.

It is hereby certified that error appears in the printed specification of the above numbered patent requiring correction as follows: Page 1, lines 84, 91 and 98, claims 2, 3 and 4, for the word "binders" read "binder"; and that the said Letters Patent should be read with these corrections therein that the same may conform to the record of the case in the Patent Office.

Signed and sealed this 8th day of May, A. D. 1928.

(Seal)

M. J. Moore,
Acting Commissioner of Patents.
